UNITED STATES PATENT OFFICE.

GUSTAV STRANDT, OF MILWAUKEE, WISCONSIN, ASSIGNOR TO MILWAUKEE DAIRY SUPPLY MANUFACTURING CO., OF MILWAUKEE, WISCONSIN, A CORPORATION OF WISCONSIN.

FEEDER FOR BOTTLES AND SIMILAR RECEPTACLES.

Application filed July 15, 1920. Serial No. 396,420.

To all whom it may concern:

Be it known that I, GUSTAV STRANDT, a citizen of the United States, residing at Milwaukee, county of Milwaukee, and State of Wisconsin, have invented new and useful Improvements in Feeders for Bottles and Similar Receptacles, of which the following is a specification.

My invention relates to improvements in feeders for bottles and similar receptacles to be delivered to filling or capping machines in an upright position, and in a regular order of succession.

The object of my invention is to provide a conveyor adapted to receive and hold a single line of receptacles, each in an upright position, and convey them in approximate contact with each other, with minimum jarring impact upon each other, or upon the walls of the conveyor, while transporting them from a loading point to the receiving machine, or to spacing mechanism interposed between the conveyor and the receiving machine; to provide spacing mechanism adapted to receive and separately deliver the receptacles in properly spaced relation to each other thru a suitable gateway guarding the entrance to the receiving machine; to provide said gateway with a yielding arm or gate adapted to control the movement of each receptacle in such a manner as to prevent either displacements or the delivery of a receptacle which has been previously displaced; to provide a form of gate which will readily yield under abnormal pressure, to avoid breaking a misplaced receptacle, and which will in such case ordinarily replace the receptacle in proper relation to the spacing mechanism; to provide for a delivery of the receptacles from the conveyor to the receiving table without tilting them or causing them to catch upon obstructing shoulders; to provide an auxiliary conveyor in such co-operative relation to the main conveyor and the spacing mechanism that receptacles which have been displaced by the spacer before reaching the gateway will ordinarily be returned into proper relation to the spacer during the interval between the time of such displacement and that of reaching the gate; and in general to provide means for feeding bottles or other receptacles

singly to a receiving machine in a predetermined spaced relation at definite predetermined intervals with minimum breakage, and with mechanical accuracy.

My invention is peculiarly adapted to be used in connection with bottle filling machines of the type disclosed in Letters Patent of the United States, granted to me on March 7th, 1916, and numbered 1,174,453.

An embodiment of my invention is shown in the accompanying drawings, in which—

Figure 1 is a plan view of my improved feeding apparatus and the receiving portion of a filling machine of the type disclosed in said former patent.

Figure 2 is a side elevation showing the means for driving the feeder from the actuating connections of the filling machine.

Figure 3 is a cross section of the main conveyor showing the means for adjusting one of the side walls to suit the requirements for bottles of differing size or capacities.

Figure 4 is a detail plan view of a modified form of gate, showing a fragment of one of the arms of the feeding wheel or star wheel.

Figure 5 is a similar view showing a further modification.

Figure 6 is a detail plan view of the star wheel and infeeding mechanism, with dotted lines indicating the mode of operation.

Figure 7 is a detail view, partly in elevation and partly in section of the so-called rotary infeeder.

Like parts are identified by the same reference characters throughout the several views.

A is the receiving table and B the turn table of a bottle filling machine of the general type disclosed in my former patent. This table constitutes the feeding table of the bottle filling machine. The table A is provided with infeeding mechanism for the filling machine, in which cam actuated arms 1 are utilized to deliver the bottles from the table A at regular intervals, and in properly spaced relation to the bottle engaging members C of the filling machine. The cam 3 is secured to the table A. The pivot shaft for the arms 1 extend thru the cam. The arms are resiliently connected with the shaft 105 by springs 4 which tend to swing them piv-

otally thereon. Stops 5 limit this swinging movement of the arms in one direction, and the roller carrying cam engaging arms 6 actuate these arms 1 in the other direction during portions of each revolution, as herein-after explained.

A main feeding conveyor, comprises a series of conveyor chains 7 operating between smooth surfaced stationary bars or slats 8. 10 This conveyor has one fixed side wall 9, and an adjustable side wall 10, the latter being parallel with the wall 9 and with the chains, but movable outwardly and inwardly with reference to the space occupied by the chains 15 to increase or diminish the width of the trough like way, along which the bottles are conveyed by the chains, whereby the width of this way may be varied to suit the requirements of bottles of differing diameters, 20 whereby they may be moved forwardly in single file.

A rotary member comprising a feeding wheel 12, designated for convenience of description as a star wheel, is horizontally disposed across the delivery end of the conveyor. The spaces between the arms of the star wheel constitute peripheral recesses or pockets to receive the bottles. This wheel is supported and actuated by a vertical shaft 30 13, located beyond the end of the conveyor, and the rim portion of the wheel is provided with a series of concavely rounded bottle receiving recesses 14, separated from each other by the radially projecting arms 15. 35 The chains 7 of the conveyor tend to carry the bottles into the recess 14 of the star wheel, each recess being adapted to receive but one bottle, and the star wheel being rotatable in the direction indicated by the arrow in Figure 1 to deliver the bottles laterally past a yielding gate 16 to an auxiliary conveyor having chains 17 similar to the chains 7 of the main conveyor, and which co-operate with the star wheel in delivering the 40 bottles across the connecting table 19 to the table A of the infeeding mechanism of the filling machine, whereby the bottles may be delivered to the table A in spaced relation to each other, and at regular intervals, corresponding with the successive bottle engaging movements of the arms 1 of the cam operated rotary infeeder, or any other bottle infeeding mechanism that might be employed for delivering the bottles to the filling machine.

The auxiliary conveyor 17 is similar in construction to the main conveyor. It is composed of chains 17 and relatively stationary bars 25, but this conveyor is short. 60 It extends merely from the inner end 26 of the main conveyor side wall 9 to a line extending laterally from the inner end of the main conveyor. It passes underneath the gate 16, and on the side adjacent to the main conveyor it extends underneath the star

wheel. The bars 25 of this auxiliary conveyor, and the bars 8 of the main conveyor, have their upper surfaces in a plane slightly below the plane normally occupied by the upper surfaces of the chains, the weight of 70 the bottles, however, being sufficient to depress the chains until the bottles move with light frictional contact along the upper surfaces of these stationary bars, whereby the bottles may be moved along the conveyor 75 without tipping or striking each other with violence. In other words, the bars 8 and 25 have a steadyng effect which is of considerable importance in preventing the bottles from being injured by striking upon each 80 other, or by catching upon the chains when being transferred laterally by the star wheel from the main conveyor to the auxiliary conveyor.

The gate 16 comprises a spring actuated 85 arm pivotally connected with a vertically disposed post 27 about which the gate actuating spring 28 is coiled. One end of this spring is secured to the arm at 28'. Its other end is connected with the post, or any 90 other stationary support, as indicated by dotted lines. The spring tends to hold the gate 16 normally in the position in which it is shown in Figure 1, with a projection 95 29 in engagement with a stop 29'. The free end of the gate arm 16, may, however, be pushed rearwardly against the tension of spring 28 whenever a laterally moving bottle strikes the gate under pressure exerted by the star wheel 12. The free end of the gate is therefore provided with a pair of anti-friction rollers 30 and 31. The axis of the roller 30 is substantially in line with the central axis of the gate arm 16, and substantially at the extremity of the arm. The axis of the roller 31 is offset rearwardly from said line, and is also located nearer to the supporting pivot shaft 27, the arrangement being such, however, that these two rollers are supported in proximity to each other, 105 and are adapted for simultaneous bearing contact with the bottle, but allowing a bottle to be received between them sufficiently to hold it from snapping out on the table 19 while pressing it either into the adjacent star wheel pocket or against the engaging end of the star wheel arm until the latter passes it and allows the bottle to be placed by the gate into the next pocket. The rollers 110 are free to revolve upon their vertical axes, and therefore allow a bottle to be transferred by the star wheel from the main conveyor to the cross conveyor without encountering such resistance as to injure the bottle, 115 or cause it to be thrown or advanced violently by the reaction of the spring 28. Suitable means are provided for adjusting the tension of the spring, which should be no greater than is necessary to hold the bottles in engagement with the star wheel during 120 125 130

the transferring operation. The gate is preferably provided with a resilient arm 33 to guide the bottles rearwardly into the space between the star wheel and the relatively stationary curved guard rail 34.

With the gate arm 16 in its normal position, as shown in Figure 1, the bottles which are properly received in the recesses 14 of the star wheel may pass thru the gate either 10 with little contact upon the rollers 30 or 31, or with no contact thereon. But it sometimes occurs that a bottle will engage the advancing shoulder 38 of one of the star wheel arms 15 in such a manner that pressure 15 sure of the shoulder against the bottle will tend to push it outwardly from the axis of the star wheel, and the bottle will then become engaged between this shoulder and the roller 30. The gate will nearly always 20 be effective by reason of its resilient pressure and outwardly or forwardly swinging movement, to hold the bottle against the star wheel arm, and allow it to advance with a pivoting movement until it can be pressed 25 by the gate into the star wheel socket which should have received it in the first instance.

At rare intervals, however, the bottle will be so engaged by the star wheel arm that the gate will be ineffective to advance it with 30 the pivoting movement above described. In that event, the gate will continue to yield, but the second roller 31 will hold the bottle until the star wheel arm passes it, the bottle tending to rotate with the rollers 30 and 31 35 so that the bottle rolls across the end of the engaging arm until it can be pushed into the next pocket. The arrangement is such that the other bottles cannot advance, the engaged bottle being partially on the main 40 conveyor until allowed to pass entirely thru the gate. A movement of this kind will ordinarily occur only in cases where lettering or other raised projections on the bottle, interfere with the normal operation of the 45 feeder. In normal operation, the bottles will move smoothly and without chittering upon each other, and will be delivered by the main conveyor successively into the successive star wheel pockets or recesses, whereupon they 50 will be held therein by the rearward pressure exerted by the chains which continue to move with light friction along the bottoms of the bottles until they have passed thru the gate into the space between the wheel 55 and the guard rail 34, whereupon they will be held in the star wheel recesses by said guard rail while they are being pushed across the table 19 to a position in which they may be successively engaged by the 60 arms 1 of the filler machine infeeding mechanism.

Referring to Figure 2, it will be observed that my improved feeder may be driven from a horizontally disposed shaft 40 of the 65 filling machine, by means of the sprocket

chain 41 extending over sprocket pulleys 42 and 43. Motion is transmitted from the sprocket pulley 43 to the star wheel thru the pulley shaft 44, bevel gear wheels 45 and 46 and vertical shaft 18, upon which the star 70 wheel is mounted.

Motion is also transmitted from shaft 44 thru sprocket pulley 50, chain 51 and sprocket pulley 52 to the shaft 53 at the rear end of the conveyor, this shaft having suitable sprocket pulleys, over which pass the chains 7 and 25. The sprocket pulleys at the outer or forward ends of the respective conveyors may, of course, be arranged to run idly upon their respective shafts, or if 80 desired, these shafts may run as idle shafts.

In Figure 3, it will be observed that the bars 8 constitute, in effect, a part of a table along which the bottles are fed by the chains. The side wall 10 is connected with this table by brackets 54 secured to the table and slides 55, connected with the wall 10, set screws 56 being employed to move the slides along the brackets in a well known manner, the brackets being provided with 85 suitable gage marks indicating the proper position in which to adjust the wall 10 for bottles of any given size.

Referring to Figure 4, it will be observed that the gate or gate arm 16^a is pivoted to a shaft 27^a as in Figure 1. But in substitution for the rollers 30 and 31, I may employ the curved guard wing 56', the hub 57 of which will, to some extent, function similarly to the roller 30, and on the back side 100 of this wing 56' I provide it, or the hub 57, with an ear 58 which is connected by a resilient link 59 with the side wall 9 of the main conveyor at 60. This link performs the function of actuating the guard wing to 105 prevent a misplaced bottle from snapping out on the table 19. When a bottle is caught by one of the star wheel arms or prongs 51, and pushed against the end of the gate 16^a, the latter swings backwardly as does the 110 gate 16 in Figure 1. The link causes the wing 56' to swing to its dotted line position in Figure 4, by reason of its resistance to the backward movement of the ear 58. If the hub 57 fails to push the bottle into the 115 proper pocket by reason of lettering or for any other reason, the wing 56' will detain the bottle until the star wheel arm passes, whereupon the gate presses it into the next star wheel pocket under the pressure of 120 spring 28.

In Figure 5, the gate arm 16^b is provided with an end roller 30^b for contact with the bottles as in the Figure 1 form of construction. Spring 28^b corresponds with spring 28 in Figure 1. But an additional arm 62 is pivoted to the table 63 at 64 and this arm is elbowed at 65, and provided with a laterally projecting end portion 66. A spring 67 connects the arm 62 with the gate arm 130

16^b, and a bearing projection 69 has a convexly curved face 70 in contact with the stop engaging projection 29^b.

- The pivot post or pin 64 is located beyond the gate post 27^b and the arm projection 29^b, and therefore, when the gate swings outwardly, the arm 62 is pushed inwardly against the tension of spring 67, to interpose the elbowed portion 65 in the path of the bottle, if it should have any tendency to snap, or throw out laterally, in passing thru the gate. The elbow 65 therefore functions in some respects similarly to the second gate roller in Figure 1.
- It will be understood that in the illustrated embodiment of my invention the arms 1 of the infeeding mechanism of the filling machine co-operate with the star wheel not only in delivering bottles to the filler turn table in regularly spaced relation, but that the arrangement of the star wheel with reference to the infeeding mechanism is such that the cam actuated arms swing into position between the advancing bottles with a relatively quick movement determined not only by their speed of rotation but by the cam 3, after which they travel at nearly the same speed as the opposing prong arm of the star wheel, until the rear-most bottle has been engaged and pushed out of the star wheel socket upon and along the feeding table A and its guard rail 75, in a curved path leading to the turn table of the filling machine upon which each bottle thus engaged is placed by the wings or arms 1 in engagement with one of the bottle receiving members C.

The infeeder arms 1 increase in speed while delivering the bottle to the turn table, but the speed again diminishes during the final bottle placing movement, at which time they move at the same speed as the turn table. The cam 3 allows the arm 1 to swing backwardly from a radius of the infeeder during this movement, not only for the purpose of securing the described retardation, but to allow the arm to withdraw from the bottle freely with no tendency to push it away from its position in the hook shaped member C.

The shaft of the infeeder shown in the drawings revolves at twice the speed of the star wheel, but the retardation allowed by the cam is such that the outer ends of the wings 1 will move at substantially the same speed as the prongs of the star wheel while retarded, and at about four times that speed when these wings are swinging toward a radius of the infeeder under spring pressure. But the cam controls the speed at all times, and therefore no free throw results from the reaction of the springs. The quick movements allow the wings or arms 1 to pass between the bottles without striking them, and to subsequently push the engaged bottle onto

the turn table at the proper time, without striking a bottle engaging member C thereof.

The infeeder shaft, in combination with the cam, constitute means for revolving the infeeder arms at varying speeds. These arms constitute peripheral bottle propelling members or arms.

I claim:—

1. A feeder for bottles, including the combination with a rotary star wheel, of a traveling bottle support for delivering and holding bottles between the arms of the star wheel, a bottle receiving table, a resilient gate regulating the delivery of bottles by the star wheel from the traveling support to the receiving table, a set of revolving arms on said table, each adapted to remove one of the bottles from the star wheel, and means for varying the rate of movement of said arms to pass them between the bottles with a quick stroke, and to engage them while retarded.

2. A feeder for bottles, including the combination with a table over which the receptacles may be passed to a filling or capping machine, a set of cam actuated arms mounted upon said table, and each adapted to engage a single receptacle, means for revolving said arms at varying speeds to receive and deliver receptacles slowly with relatively quick intermediate movements, a bottle supporting feeding conveyor, and a rotary member adapted to engage and push bottles singly from the conveyor into position for engagement by one of said revolving arms.

3. A feeder for bottles, including the combination with a table over which the receptacles may be passed to a filling or capping machine, a set of cam actuated arms mounted upon said table, and each adapted to engage a single receptacle, means for revolving said arms at varying speeds to receive and deliver receptacles slowly with relatively quick intermediate movements, a bottle supporting feeding conveyor, a rotary member adapted to engage and push bottles singly from the conveyor into position for engagement by one of said revolving arms, and a resiliently yielding gate for regulating the passage of receptacles from the conveyor to said table.

4. The combination of a main conveyor for bottles, a rotary member at the delivery end of the conveyor having a peripheral portion extending over the delivery end of the conveyor at one side of its axis of rotation, and provided with peripheral recesses, each adapted to receive one of the receptacles, a laterally disposed auxiliary conveyor to which the receptacles may be delivered by said rotary member, a receiving table at the delivery end of the auxiliary conveyor, and means for resiliently control-

ling the transfer of the receptacles from the main conveyor to the auxiliary conveyor by pressing upon the receptacles in the direction of said rotary members during such transfer.

5. The combination of a main conveyor for bottles, a rotary member at the delivery end of the conveyor having a peripheral portion extending over the delivery end of 10 the conveyor at one side of its axis of rotation, and provided with peripheral recesses, each adapted to receive one of the receptacles, a laterally disposed auxiliary conveyor to which the receptacles may be delivered by said rotary member, a receiving table at the delivery end of the auxiliary conveyor, means for resiliently controlling the transfer of the receptacles from the main conveyor to the auxiliary conveyor by pressing upon the receptacles in the direction of 15 said rotary members during such transfer, a second rotary member provided with arms to engage and move the receptacles along said table, and means for pivotally swinging 20 said arms toward and away from radii of said member to facilitate passing them between receptacles on the receiving side, and withdrawing them from the receptacles 25 on the delivery side.
- 30 6. The combination with a main conveyor for bottles, of a rotary transferring mechanism revoluble about a vertical axis at the delivery end of said conveyor, and adapted to push receptacles laterally therefrom, and a resilient positioning device 35 adapted to press the receptacles on the conveyor in the direction of said rotary transferring mechanism to prevent transfers of receptacles which are out of proper relation 40 thereto.

- 45 7. The combination with a main conveyor for bottles, of a rotary transferring mechanism revoluble about a vertical axis at the delivery end of said conveyor, and adapted to push receptacles laterally therefrom, a resilient positioning device adapted to 50 press the receptacles in the direction of said rotary transferring mechanism to prevent transfers of receptacles which are out of proper relation thereto, said positioning device comprising a spring actuated gate having a free end portion against which receptacles may strike, and provided with anti-friction and receptacle detaining devices, 55 adapted to insure a delivery of the receptacles in a regular order of succession and with a movement corresponding to that of the rotary member.

- 60 8. A feeder for bottles, including the combination of a main feeding conveyor, a feed table, a feeding star wheel mounted to rotate horizontally thereover, and adapted to move upright receptacles laterally from the conveyor to the surface of said table, said 65 conveyor having a lateral outlet adapted to

allow upright receptacles to be conveyed thru it by the feeding wheel, and an auxiliary feeding conveyor disposed tangentially to the feeding wheel substantially at the level of the table, and adapted to co-operate with 70 the wheel in feeding bottles rearwardly on said table from said main conveyor, said feeding wheel having peripheral pockets adapted to partially receive the bottles, and said auxiliary conveyor being adapted to press the bottles 75 into said pockets during the initial portion of their movement with the wheel.

9. A feeder for bottles, including the combination of a main conveyor, a horizontally revolving feeding star wheel at the delivery 80 end of said conveyor, disposed with its axis substantially vertical and across the center line of the conveyor, and auxiliary conveying means substantially tangential to the feeding wheel, and parallel with the main 85 conveyor on the side toward which the bottles are pushed by such wheel.

10. A feeder for bottles, including the combination of a feed table, a feeding wheel thereon mounted to rotate about a vertical 90 axis, and having peripheral bottle propelling members, a feed-way leading to said wheel, and adapted to permit delivery of receptacles successively into position for engagement by said members in an upright 95 position, said feed-way having a lateral outlet thru which the receptacles may be pushed by the wheel, and a resiliently yielding member guarding the outlet, and adapted to press partially engaged receptacles 100 into full engagement by the feeding wheel members.

11. A feeder for bottles, including the combination of a feed table, a feed-way adapted to permit delivery of receptacles to 105 the table singly, and in an upright position, means for pushing the receptacles one by one laterally from said feed-way at its delivery end, and a resiliently yielding member adapted to hold the receptacles in positions 110 for engagement with said pushing means during their lateral movement.

12. A feeder for bottles, including the combination of a feed table, a feed-way adapted to permit delivery of receptacles to the table in an upright position, means for successively pushing single receptacles laterally from said feed-way at its delivery end at regular intervals, a resiliently yielding member adapted to hold the receptacles in position for engagement by said pushing means, and a conveyor adapted to receive receptacles from the feed-way, and co-operating with said resiliently yielding member in holding the receptacles in engagement with 120 said pushing means.

13. A feeder for bottles, including the combination of a main feed-way, a table adapted to receive receptacles from the feed-way in an upright position, a rotary mem- 130

ber, provided with arms adapted to push the receptacles one by one laterally from the feed way to the table, a resiliently yielding guard disposed at one side of the feed-way 5 out of the normal path of properly engaged receptacles, and adapted to receive the pressure of receptacles engaged by the outer portions of said arms, said yielding guard being provided with a plurality of projections 10 adapted for successive yielding engagement with a receptacle, to press the same in the direction of said rotary pushing means, and a curved stationary guard co-operative therewith to cause the receptacles to follow 15 a curved path along the table.

14. A feeder for bottles, including the combination of a feed-way, provided with raised sides, one of which terminates adjacent to the delivery end of the feed-way to 20 provide a lateral outlet therefrom, a rotary pushing wheel having arms between which single receptacles may be engaged and pushed thru said outlet, and a resiliently yielding member guarding said outlet at a 25 sufficient distance from the rotary pushing means to be out of the normal path of receptacles properly engaged between said arms, said yielding member being adapted to allow the receptacles to pass thru said 30 outlet, under pressure exerted by the end of one of the arms, and to push the same in the direction of one of the spaces between the arms.

15. The combination with a feed-way 35 adapted to deliver bottles in a single series, and in an upright position, to a rotary spacing wheel, a rotary spacing wheel provided with bottle engaging arms, adapted to deliver the bottles laterally from said feed-way, said feed-way having raised side walls, one of which terminates near its delivery end to provide an outlet for a lateral delivery of the bottles, a spring actuated guard lever 40 pivotally supported at a point laterally distant from the feed-way, and having an arm normally closing a portion of said outlet, with sufficient space between its extremity and the spacing wheel to allow a bottle to 45 pass when properly engaged by said wheel.

16. The combination with a feed-way 50 adapted to deliver bottles in a single series, and in an upright position, to a rotary spacing wheel, a rotary spacing wheel provided with bottle engaging arms adapted to deliver the bottles laterally from said feed-way, said feed-way having raised side walls, one of which terminates near its delivery end to provide an outlet for a lateral delivery of the bottles, a spring actuated guard lever 55 pivotally supported at a point laterally distant from the feed-way, and having an arm normally closing a portion of said outlet with sufficient space between its extremity and the spacing wheel to allow a bottle to 60 pass when properly engaged by said wheel, 65

and a plurality of bottle engaging members carried by said lever, and adapted to successively receive the pressure of bottles conveyed by the pushing wheel at an abnormal distance from its center.

17. In a feeder for bottles, the combination of a set of depressible conveyor chains supported for substantially horizontal movement along a feed-way, and interposed relatively stationary bars having upper surfaces 75 slightly below the normal level of the chains, and adapted to be exposed to light frictional contact with receptacles by depression of the chains under the weight of such receptacles.

18. In a feeder for bottles the combination of a set of depressible conveyor chains supported for substantially horizontal movement along a feed-way, and interposed relatively stationary bars having upper surfaces 80 slightly below the normal level of the chains, adapted to be exposed to light frictional contact with receptacles by depression of the chains under the weight of such receptacles, a set of side walls for said way, and means for adjusting one of the side 85 walls laterally with reference to the chains to increase or diminish the width of the way.

19. In a bottle feeder the combination with a conveyor adapted to move a line of 95 bottles in one direction, a rotary bottle spacing member having arms adapted to deliver bottles from the conveyor in another direction, a pivoted gate arm projecting toward the conveyor along the path of the delivered 100 bottles and means for allowing said gate arm to yield in a swinging movement away from said rotary member when the latter presses a bottle against the arm.

20. In a bottle feeder the combination 105 with a conveyor adapted to move a line of bottles in one direction, a rotary bottle spacing member having arms adapted to deliver bottles from the conveyor in another direction, a pivoted gate arm projecting toward the conveyor along the path of the delivered 110 bottles and means for allowing said gate arm to yield in a swinging movement away from said rotary member when the latter presses a bottle against the arm, said arm having a 115 bottle engaging roller at its extremity.

21. In a bottle feeder the combination with a conveyor adapted to move a line of bottles in one direction, a rotary bottle spacing member having arms adapted to deliver 120 bottles from the conveyor in another direction, a pivoted gate arm projecting toward the conveyor along the path of the delivered bottles and means for allowing said gate arm to yield in a swinging movement away 125 from said rotary member when the latter presses a bottle against the arm, said arm having a bottle engaging roller at its extremity and another roller adjacent thereto and offset from the center line of the arm in the 130

general direction of the delivery side of the spacing member.

22. In a bottle feeder the combination with a conveyor adapted to move a line of bottles in one direction, a rotary bottle spacing member having arms adapted to deliver bottles from the conveyor in another direction, a pivoted gate arm projecting toward the conveyor along the path of the delivered 5 bottles and means for allowing said gate arm to yield in a swinging movement away from said rotary member when the latter presses a bottle against the arm, said arm having a bottle engaging roller at its extremity, an-

other roller offset toward the spacer from 15 the axis of said arm and an auxiliary resiliently yielding member extending from said arm between the rollers and its pivoted end along a curved line in the arc of a circle substantially concentric with the spacing 20 member.

In testimony whereof I affix my signature in the presence of two witnesses.

GUSTAV STRANDT.
